UNITED STATES PATENT OFFICE.

JOHN C. HEILMANN, JR., OF CINCINNATI, OHIO.

CANDY-FORMING MACHINE.

SPECIFICATION forming part of Letters Patent No. 650,841, dated June 5, 1900.

Application filed August 18, 1899. Serial No. 727,631. (No model.)

To all whom it may concern:

Be it known that I, JOHN C. HEILMANN, Jr., a citizen of the United States, and a resident of Cincinnati, Hamilton county, State of Ohio, have invented certain new and useful Improvements in Candy-Forming Machines; and I do declare the following to be a description of the invention sufficiently clear, full, and exact to enable others skilled in the art to which it appertains to make and use the same, attention being called to the accompanying drawings, with the reference-numerals marked thereon, which form also a part of this specification.

15 This invention relates to machines which by a rolling operation form pieces of uniform size and shape out of a material which is of plastic or dough-like consistency. Machines of this kind are used in connection with the manufacture of confectioners' and bakers' goods, and my invention is described as intended for such purpose.

It consists of a certain device whereby the material to be worked up and formed into pieces is supplied in fixed and measured quantities, so that the resulting forms and objects are all perfectly alike as to size and shape.

25 My invention consists, further, of the construction of this device and of certain details of construction of other parts of the machine, all as more fully set forth hereinafter.

30 In the following specification and particularly pointed out in the claims at the end thereof is found a full description of my invention, together with its operation, parts, and construction, which latter is also illustrated in the accompanying two sheets of drawings, in which—

Figure 1 is a front view of the machine. 40 Fig. 2 is a top view thereof. Fig. 3 is an end view showing the left end as viewed in Fig. 1. Fig. 4 is a rear view of the left portion of Fig. 1. Fig. 5 shows a part of the machine in a sectional view taken on a plane passing 45 across the discharge-outlet of the receiver. Fig. 6 is a sectional detail view of the measuring device.

The mass or dough to be worked up is fed from a receiver 8, to which it is supplied 50 through a hopper 9, which for convenience of filling is surrounded by a pan-shaped shelf 11. After the hopper is filled a plunger 12

is caused to bear on top of the mass to force the same gradually down into the receiver. This plunger is pivotally supported on a lever 55 13 and loaded by a weight 14, adjustably mounted on this lever. By changing the position of this weight the pressure of the plunger against the mass may be correspondingly adjusted. The mass is fed from the receiver 60 through a discharge-opening 15 in one of its ends, being moved by means of a screw 16, mounted upon a shaft 17, supported in bearings 10 and 20, of which the first is formed in the other end of the receiver. Shaft 17 is 65 driven from shaft 18 by means of gear connection 19, of which latter there is preferably a set of graduated sizes, as shown, to provide for adjustment of speed. The gear-wheels of the set on shaft 17 are loosely mounted; 70 but any one of them may be positively connected by means of a sliding key (not shown) operated for adjustment by means of a rod 21 and a lever 22, which is then locked in position, the whole being a well-known expedient. Shaft 18 constitutes the drive-shaft 75 of the machine and may be operated in any suitable way—as, for instance, by means of a pulley 23. The mass discharging from opening 15 enters a measuring-cup, (see Fig. 80 6,) the bottom and side of which are formed of two independent members. The bottom is formed by the end of a stud 24, supported in a bearing 25, and the side is formed by a hollow cylinder 26, fitted to and mounted on stud 24 in a manner to be capable of a sliding motion thereon. There is a certain distance between the end of this stud and the discharge-opening of receiver 8, which space when the cup is to be filled is 85 bridged by cylinder 26. The parts remain in this cup-forming position a certain length of time, which is sufficient for the cup to become filled, a certain part—say about half or more or less—of the revolution of the machine being apportioned for such purpose. After that the movable part of the cup recedes from the opening of receiver 8, leaving 90 its contents unsupported, as shown in Figs. 1 and 2. At this time a rotating knife 30, mounted by means of a hub 27 on shaft 18 and driven thereby, passes close in front of discharge-opening 15, cutting off the exposed mass protruding therefrom and causing the 100

same to drop off from the end of stud 24. This end is undercut, as shown, to facilitate the cut-off portion of the mass to clear the same. The detached piece drops first into a 5 hopper 28, by which it is guided into the forming device, consisting of two complementary parts, between the oppositely-concaved surfaces of which the piece now is rolled to the desired shape. These parts consist, on 10 the one side, of a roller 29, containing in its concaved face one of the forming-surfaces, while the opposite forming-surface, acting in conjunction therewith, is contained in a stationary concaved or gutter-shaped structure 15 31, fitted closely to and following to a certain extent around the periphery of roller 29. This forming-gutter is supported by a bracket 32, secured to the machine-frame. To facilitate entrance of the dropping-piece between 20 these forming-surfaces, I provide an additional roller 33 above the upper end of gutter 31 and below hopper 28. Its face is opposite the face of roller 29 and correspondingly concaved, so as to act in conjunction with the 25 other forming-surfaces. The shape of the pieces to be formed in this case being a ball, the forming-surfaces are each shaped accordingly—that is, the faces of rollers 29 and 33 and the inner surface of structure 31, the one 30 opposite roller 29, are each concaved semicircularly. While the cut-off piece is thus given its shape by being rolled between the forming-surfaces, the measuring-cup is filling again, cylinder 26 having meanwhile returned 35 to form such cup again. It is evident that during the time while the cup is not in position discharge-outlet 15 must be closed, which is done by knife 30 while passing close in front of this opening and is of sufficient width 40 to remain in front thereof until cylinder 26 has returned and re-formed the cup.

To prevent adherence of the mass to the forming-surfaces while being rolled between them and to facilitate this operation, I provide 45 a device which supplies a suitable medium, like powdered starch or flour, to these surfaces. It consists of a receptacle 34, supported on a standard 35 and so located as to bring its perforated bottom above roller 29, 50 upon the face of which its contents are sprinkled. The discharge of the sprinkling material is effected by an agitator 36, operated by gear-wheels 37 and 38.

The different parts of the machine are 55 driven from shaft 18, which is supported in bearings 39 and, as already stated, drives screw-shaft 17 of the feed device by means of gear-train 19 and has also knife 30 mounted on it. By means of bevel-wheels 41 it operates 60 a shaft 42, supported in bearings 43 and which drives the other movable parts of the machine. By means of gear-wheel 38 it operates gear-wheel 37 on the agitator-shaft of the sprinkling device. By means of a sprocket-wheel 44 and a chain 45 it operates rollers 29 and 33, which for such purpose are each 65 respectively mounted on one end of shafts 46

and 47, each suitably supported, and the other ends of which shafts carry each a sprocket-wheel numbered, respectively, 48 and 49, each 70 also engaged by chain 45. 51 is an idler sprocket-wheel the function of which is to change the direction of motion of the sprocket-chain. The movable part 26 of the measuring-cup is reciprocated by means of a cam 52, 75 acting upon a lever 53, the forked end of which engages said part 26. This lever is supported on a post 54 and held in contact with cam 52 by means of a spring 55. In place of the cam shown one with a groove receiving the end of lever 53 might be used, in which case spring 55 would not be required. The connection of this lever to part 26 is such as to permit ready removal of this latter in cases when pieces of different sizes, requiring 80 more or less material, are to be dealt out. Stud 24 and the end of receiver 8 containing the discharge-opening are also removable for such purpose. The parts of the forming device, rollers 29 and 33, and gutter 31 are also 85 interchangeable in case pieces of different size or shape are to be produced. Hopper 28 is also arranged to follow these adjustments, for which purpose it is in two parts, each secured by set-screws, so that its sides may be 90 moved to or from each other.

To prevent adherence of the mass to the knife, the same is caused to pass at every revolution through a water-containing tank 56, whereby the blade is kept smooth and 100 clean. Splashing of this water is prevented by fenders 57. More or less of this water on the blade of the knife is apt to be transferred onto the material, wetting the cut-off pieces to some extent, for which reason they are 105 caused to discharge first upon the perforated surface of a drainer 58. This surface is inclined, and while the formed pieces roll down thereon the water is given a chance to drain off, the collected drainage passing away 110 through a waste-pipe 59.

The pressure of the feed-screw within receiver 8 causes a separation of more or less of the liquid matter from the more solid substances, which liquid collects in the lowest 115 part of the receiver, from which it is drained by a pipe 61, which discharges into a vessel 62.

Having described my invention, I claim as new—

1. In a forming-machine, the combination 120 of a receiver 8, having a discharge-outlet 15, a feed device causing the contents of the former to pass through this opening, a forming device, a cup-shaped measuring device interposed between this latter and receiver 8, and 125 means to cause it to travel with a reciprocatory motion to a position opposite opening 15 to be filled therefrom and afterward to recede from it, and to deliver its contents to the forming device.

2. In a forming-machine, the combination 130 of a feed device, a forming device consisting of a roller 29 and a gutter 31 fitted against part of the periphery of the former, the op-

posing surfaces of both being concaved to form a space between them, a roller 33 to start the substance into this space, being mounted opposite roller 29 and equally concaved and a hopper directing the substance discharged from the feed device so as to be received between these two rollers.

3. In a forming-machine, the combination of a forming device, a receiver 8, from which the substance to be worked up is fed to the former, a hopper 9, through which this receiver is supplied, and a plunger in this hopper to move the substance therein, a lever 13, to which this plunger is connected and a weight adjustably mounted on this lever for the purpose described.

4. In a forming-machine, the combination of a receiver 8 having an outlet-opening, means to cause the contents thereof to discharge through this opening, a cup-shaped measuring device receiving this discharge, a knife severing the issuing mass between the outlet-opening of the receiver and the open part of the measuring device whenever this latter is filled, a forming device by which the detached portion of the mass is shaped and means whereby the portion detached by the knife is transferred from the measuring device to the forming device.

30 5. In a forming-machine, the combination of a feed device, a cup-shaped measuring device into which it discharges, a knife adapted to pass between the two to sever the mass when the latter device is filled, a water-receptacle through which the knife passes between operations having fenders 57, and a forming device which receives the mass from the measuring device in fixed quantities.

6. In a forming-machine, the combination of a feed device, a measuring device into which it discharges, a knife adapted to pass between the two to sever the mass when the latter device is filled, means to moisten the

knife-blade between operations, a forming device which receives the mass from the measuring device in fixed quantities, a drainer upon which the formed articles are discharged from the forming device, and means to collect and dispose of the received drainage.

7. In a forming-machine the combination of a receiver 8, having an outlet-opening 15, a cup-shaped measuring device adapted to be moved to and from this opening, receiving the discharge therefrom while opposite it, a rotary knife adapted to pass between the two when the cup is filled, the same being of an extended width, thereby holding opening 15 closed while the measuring-cup discharges its contents and until the same is in position again for filling and a forming device which receives the contents of the measuring-cup.

8. In a forming-machine, the combination of a receiver 8, having an outlet-opening 15, a cup-shaped measuring device consisting of a stud 24, supported with its end opposite opening 15 with a space between the two, a cylinder 26 fitted thereto in a manner to have a sliding motion thereon, means to reciprocate it on stud 24, a knife operating in front of and across the opening 15 and a forming device receiving the contents of the measuring device.

9. In a forming-machine, the combination of a receiver 8, having a discharge-outlet 15 in one of its ends, a hopper through which it receives its supply, a feed-screw by means of which its contents are moved out through opening 15, a drainage-outlet 61 for liquid matter and a forming device receiving the plastic contents issuing from opening 15.

In testimony whereof I hereunto set my hand in presence of two witnesses.

JOHN C. HEILMANN, JR.
